UNITED STATES PATENT OFFICE.

JOHN T. STORY, OF NEW YORK, N. Y.

HAIR INSOLE.

1,351,726.

Specification of Letters Patent. Patented Aug. 31, 1920.

Application filed February 2, 1920. Serial No. 355,832.

To all whom it may concern:

Be it known that I, JOHN T. STORY, a citizen of the United States, residing at New York, in the county of New York and State of New York, have invented certain new and useful Improvements in Hair Insoles, of which the following is a specification.

The object of this invention is to provide a new and improved insole composed chiefly 10 of layers of hair loosely matted and sewed together.

Another object of the invention is to provide a process for making the insole.

These and other features of the invention 15 will be illustrated in the drawings, described in the specification and pointed out in the claims at the end thereof.

In the drawings,

Figure 1 is a perspective view of the insole, the upper and lower hair layer being 20 partially turned back to expose the intermediate layer.

Fig. 2 is a sectional view of the insole on the line 2^x-2^x of Fig. 1.

25 In the drawings, like reference numerals indicate like parts.

In the drawings, reference numeral 1 indicates the insole made up of an intermediate layer 2 of paper stock or felt paper or 30 canvas and of the top and bottom layers 3 and 4 made up of hair and suitable backing and binding material 5 and 6 for holding the hair together and in shape.

Goat hair or cow hair is preferably used 35 although it is understood that other kinds of hair can be used as well. This hair is first teased by a picking machine which makes it soft and takes out the lumps and cleans it as well. This hair is then evenly 40 distributed on a web of felt paper 2, the upper side of which is coated lightly with fresh paste so that the hair will adhere thereto. A web of this felt paper is first stretched on the table and the hair is loosely 45 sifted thereon so as to be evenly distributed thereover to the proper thickness. This layer may be fed directly and continuously to the web by the picking machine and a web about 36" wide is preferably used in 50 either case whether the hair is placed thereon by hand or machine.

The layer of hair is then preferably covered over with a web of thin paper and the 55 felt paper, the layer of hair and the paper cover are rolled up into a roll in which form the material is kept until the paste or glue

has had an ample time to dry. After the paste is dried the felt paper and the layer of hair with the paper cover removed therefrom are passed through a sewing machine 60 which sews a number of parallel rows of stitches through the layer of felt paper and hair, securely holding the layer of hair and felt paper together. These stitches run preferably several rows to the inch. The 65 paper web covering the hair is rolled up as fast as the hair is uncovered in the sewing operation and the sewing progresses as fast as the hair is uncovered, so that only a small area of the unsewed hair and felt paper is 70 exposed at a time. This completes the upper layer. The felt paper and the hair are rolled up as fast as it is sewed.

It is thereafter unrolled with the blank side up and another layer of hair is put 75 on the blank side as follows:

A web of cheese cloth or light buckram 5 or 6 or crinoline is first stretched on a table. Any light fabric of coarse weave will answer the purpose. The hair is then 80 loosely sifted on the fabric so that a layer of it is evenly distributed over it to the proper thickness. The fabric is coated with a sizing, that assists in holding it in place. The hair may or may not be covered 85 with a web of paper and it is then rolled into a roll. The fabric and hair are then passed through the sewing machine which stitches several rows to the inch. The upper layer of the felting paper is then lightly 90 coated with paste and the layer of fabric and hair is placed thereon and the paper and the two layers of hair are then rolled into a roll, in which shape it is left to dry and set.

95 The web thus formed is then passed through a cutting machine which cuts the insoles by a punching die from the web of three layers and each insole is sewed close to the margin thereof with a row of stitching so as to hold the three layers together at the edge.

As a substitute for the marginal row of stitches or in addition thereto, the layers may be held together by stitches passing 105 around the edge of the insole in the manner ordinarily known as over-casting.

It is well known that hair has hygroscopic qualities that are peculiar to itself. It readily absorbs and holds moisture and 110 will therefore absorb the dampness from the feet and stockings and keep them dry

and will keep the shoes dry as well when it is used as an insole. This moisture is easily removed by removing the insole from the shoes and separately drying them, after which they may be used again. The insoles made in this manner are cheap and durable and are capable of keeping the wearer's feet warm and dry and form a good cushion for the feet and are pliable and sanitary as well.

It will also be understood that the second layer of hair may be sifted directly onto the intermediate layer in the same manner that the first layer is placed thereon and the three layers can be passed through the sewing machine which will save the three layers simultaneously so that one sewing operation will be sufficient for both layers of hair and the cheese cloth, buckram or crinoline may then be omitted.

I claim:

1. An insole having an intermediate layer of binding material, a layer of hair loosely disposed on one side thereof and stitched thereto, a layer on the other side formed of a thin fabric with a layer of hair loosely

disposed thereon and stitched thereto, the second layer being fastened to the intermediate layer by an adhesive.

2. An insole having an intermediate layer of binding material, a layer of hair loosely disposed on one side thereof and stitched thereto, a layer on the other side formed of a thin fabric with a layer of hair loosely disposed thereon and stitched thereto, the second layer being fastened to the intermediate layer by an adhesive, the edge of the insole being finished by stitching to bind the parts together.

3. The process of making insoles which consists of first coating an intermediate layer on one side with an adhesive and then evenly covering it with a layer of hair, stitching the hair to the intermediate layer then fastening by an adhesive to the other side of the intermediate layer a layer of hair and fabric sewed together, the hair and fabric being fastened to the intermediate layer by an adhesive, and cutting the insoles from the web thus formed.

In testimony whereof I affix my signature.
JOHN T. STORY.
